UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A BRUSH-BACK OR SIMILAR ARTICLE.

SPECIFICATION forming part of Design No. 22,627, dated July 18, 1893.

Application filed May 18, 1893. Serial No. 474,706. Term of patent 3½ years.

To all whom it may concern:

Be it known that I, CHARLES OSBORNE, of the city, county, and State of New York, have invented a new and Original Design for a 5 Brush-Back or Similar Article, of which the following is a full, clear, and exact description.

Reference is to be had to the accompanying drawings forming a part of this specification, in which Figure 1 is a side elevation of a brush having a back and handle showing my design; and Fig. 2 is a plan view of the same.

The leading features of my design are the 15 wreath-like border formed of connected scrolls, and the leafy rosettes at intervals in the border.

10 is the brush back and 11 the handle. The brush back, when viewed in elevation, has its edges slightly inclined, and on the top 20 of the back and handle, near the edge, and extending completely around them, is a border formed of raised scroll-like figures connected end to end, while at intervals in the border are produced the leafy rosettes 12 25 which have scalloped edges.

I claim—

The design for a brush back or similar article herein shown and described.

CHARLES OSBORNE.
